(57) CLAIM

The ornamental design for a wallet, as shown and described.

DESCRIPTION

FIG. 1 is a top front perspective view of the wallet, showing our new design;

FIG. 2 is a front elevation view thereof;

FIG. 3 is a rear elevation view thereof;

FIG. 4 is a top plan view thereof;

FIG. 5 is a bottom plan view thereof;

FIG. 6 is a left side elevation view thereof, shown at three times the scale of the other views for clarity;

FIG. 7 is a right side elevation view thereof, shown at three times the scale of the other views for clarity;

FIG. 8 is a top front perspective view thereof, showing the wallet in a folded position; and,

FIG. 9 is a top front perspective view thereof, showing the wallet in use.

The broken lines shown in FIGS. 1-8 depict stitching that forms no part of the claimed design.

The broken lines in FIG. 9 showing a pair of jeans depict environment while the wallet is in use, and forms no part of the claimed design.

The stippling shown on the wallet represents a contrast in color.

1 Claim, 4 Drawing Sheets
